UNITED STATES PATENT OFFICE.

SETH SALOMON ERICKSON, OF NEW YORK, N. Y.

INTERNAL-COMBUSTION ENGINE.

1,172,124.

Specification of Letters Patent. Patented Feb. 15, 1916.

Application filed May 20, 1915. Serial No. 29,309.

To all whom it may concern:

Be it known that I, SETH SALOMON ERICKSON, a citizen of the United States, and a resident of the city of New York, 5 borough of the Bronx, in the county of Bronx and State of New York, have invented a new and Improved Internal-Combustion Engine, of which the following is a full, clear, and exact description.

10 Among the principal objects which the present invention has in view are: to reduce the number of friction-producing members; to increase the efficiency of the engine; and to simplify the engine construction.

15 *Drawings.*—Figure 1 is a side elevation of an engine constructed and arranged in accordance with the present invention; Fig. 2 is a longitudinal vertical section of said 20 engine; Fig. 3 is a vertical cross section taken as on the line 3—3 in Fig. 1; and Fig. 4 is a cross section taken as on the line 4—4 in Fig. 1.

25 *Description.*—As seen in the drawings, a plurality of power units constructed and arranged in accordance with the present invention may be employed to operate upon the single crank shaft 9. In the engine shown in the drawings, the bearings 10 for 30 the said shaft are formed in supports mounted on a base plate 11. At suitable intervals, cranks are provided, with which connecting rods 12 are engaged. The rods 12 are employed, as in engines of conventional type, to transmit power to the crank shaft. In the present construction, the connecting rod 12 of each unit is operatively connected to two pistons 13, a single wrist pin 14 being employed for this purpose.

35 40 The pistons 13 are preferably of uniform size and are mounted in cylinders 15. The cylinders 15 are provided with alined guide slots 16, through which extends one of the wrist pins 14. Each wrist pin 14 is passed 45 through bores provided therefor in the pistons 13 and in the bridges 17 thereof. Each connecting rod 12 operatively engages one of the wrist pins 14, being provided for this purpose with a bearing box 18, which has a 50 cap 19. The box and cap referred to are machined to form wearing surfaces for engaging the planed surfaces of bosses 20. In this manner, it will be observed, the head of the connecting rod 12 is maintained in 55 accurate alinement with the crank of the shaft 9, with which it is engaged.

The cylinders 15 are bolted to face plates 21, round seats being provided for the said cylinders to form airtight joints and to close the lower ends of the compression 60 chambers 22. The chambers 22 are closed at the upper end by a barrel or apron 23 of the pistons 13, the joints of the said apron and side wall of the said chambers being sealed by packing rings 24. Admission 65 to the chambers 22 is attained through the ports 25 when the valves 26 are drawn from their seats in the valve casings 27. Each valve 26 is held seated by a spiral spring 28, which infolds the stem 29 extended outward from the valve. Each casting is furnished with a series of circularly disposed perforations 30 which form inlets to the casings 27 and to the chambers 22 when the said valves 26 are drawn from 70 their seats by suction of the pistons 13. This construction is shown best in Fig. 3 of the drawings.

The upper ends of each pair of cylinders 15 are closed by a single head 31. The 75 heads 31 are each provided with recesses 32 for alinement with the cylinders 15 to form compression and clearance spaces in the explosion chambers of said cylinders. The recesses 32 are each connected with a 80 centrally disposed ignition chamber 33, to which oil or other suitable combustible is admitted through a port normally closed by a spring-seated valve 34, as seen best in Fig. 2 of the drawings.

85 The ignition chamber 33 and the cylinders 15 are suitably cored to form intercommunicating water jackets for cooling the walls of said chamber and cylinders. The circulating system for the water furnished to said jackets, is not disclosed in the 90 present application.

95 The explosive fuel employed in the present engine is a suitable mixture of oil, preferably kerosene, and air. The compression 100 necessary to the explosion is provided by the pistons 13, which during the power stroke, compresses air in the chambers 22, said air having been drawn into the chambers when the said pistons are carried on 105 their return, or what is usually known as compression stroke. The air having been drawn into the chambers 22, is compressed by the pistons in their power strokes until at the end thereof, the intake ports 35 are 110 exposed.

The ports 35 open into the explosion

chamber of each cylinder and are formed at the end of inclined passages 36, which passages, as shown best in Fig. 3 of the drawings, are slightly tapered to produce a nozzle-like action when delivering the compressed air from the chambers 22 and connecting tube 37, which operatively connects each passage 36 with the outlet port 38 in each of the chambers 22. The purpose of the construction described, where the passage 36 is inclined and contracted, is to deliver the air admitted after each explosion, to the combustion chamber in an upward jet to avoid the exhaust port 39 and to scavenge the combustion chambers. It will be observed best by reference to Fig. 3 of the drawings, that prior to the exposure of the port 35, the exhaust port 39 has been fully open. It follows from this that prior to the introduction of the compressed air from the chamber 22 in each cylinder into the combustion chamber thereof, the explosion pressure of the explosion has been substantially diminished.

In practice it is found that the escape of the burned gases is so rapid that at the moment of exposing the port 35, the pressure in the explosion chamber is atmospheric or less than atmospheric pressure. When, therefore, the compressed air is admitted, the burned gases are ejected from the combustion chamber. It will also be noticed that at the moment of the introduction of the compressed air, the pistons 13 are at the points of their most diminished movement, the connecting rod passing the dead center thereof.

The oil above referred to is delivered to each of the ignition chambers 33 by small pumps 40. Each pump 40 has a miniature plunger 41, which is provided with a stem 42, the end whereof extends into the path of the cap 19 of each connecting rod 12 to be engaged thereby when said connecting rod is lifted. Each stem 42 is depressed by a spiral spring 43, as seen best in Fig. 2 of the drawings. In the fully depressed position of the plunger 41, the delivery end of an oil supply pipe 44 is exposed to permit the introduction of oil therefrom into the cylinder of the pump 40 above the said plunger. The quantity of oil delivered is properly proportioned to the amount of air with which the chamber 33 is supplied from the cylinders 15 and which is compressed in the said ignition chamber by the pistons 13 in the course of the elevation thereof. It will be noted that a partial compression of the air in the chamber 33 has been arrived at prior to the engagement by the cap 19 of the stem 42 which inaugurates the operation of the plunger 41.

Operation.—The engine and units thereof are of the type known as two-cycle engines, or of that character of engine where the

scavenging of the burned gases is incident to the delivery of the fuel charge thereto. In the present engine, the pistons 13 are simultaneously depressed by the explosion of the fuel charge in the ignition chamber 33, the expanding gases therefrom being delivered by the passages 45 to the recesses 32 communicating with each of the cylinders 15. The ignition of the charges may be effected by any known and preferred method. The pressures exerted by the pistons 13 upon the wrist pin connecting the same are equalized. The power stroke delivered to the crank shaft 9 by each rod 12 is thus multiplied by the number of pistons 13 connected therewith. As each piston moves on its power stroke, the air for each of the chambers 22 is compressed, the pressure gradually increasing in each chamber until at the approximate end of the power stroke of each of the pistons, the said pistons partially uncover the ports 35 in each cylinder. Immediately preceding the uncovering of the ports 35, the port 39 in each cylinder has been fully opened, prior to the introduction of air from the chambers 22, tube 37 and passage 36. During the swing of the lower end of the connecting rod 12 past the dead center at the outer side of the shaft 9, the air which has been compressed and which is being delivered during this period of time to the combustion chambers, has opportunity afforded to scavenge the combustion chambers of the cylinders, to remove the dead or burned gases therefrom. When now in the rise of the pistons 13, the air is trapped in the combustion chambers, it is further compressed in the said combustion chambers and in the ignition chamber 33 communicating therewith. This compression continues until the pistons 13 have been completely raised. At the final portion of the compression stroke of the pistons, the cap 19 of the corresponding connecting rod 12 engages the stem 42 of the pump 40 to lift the plunger 41 of the said pump to inject oil in the chamber 33. The valve 34 is lifted by the pressure below and when opened, serves to spread the oil, which is thus forced past the stem, nebulizing it as it passes into the said ignition chamber 33.

The valve 34 is seated by a spring 46 which infolds a stem pendant from the valve 34. It will be noted that the plunger 41 does not engage the stem of the valve 34 and that the spring 46 is permitted to seat the valve 34 at the instant of the suspension in the upward stroke of the plunger 41 and prior to the ignition of the explosive fuel in the chamber 33. The timing of the ignition is managed in this engine in a manner similar to that provided for engines of conventional construction.

While there has been herein described a form of engine employing a single connect-

ing rod operated by twin or paired pistons, it will be understood that the number of pistons may be augmented. While the construction is not limited to the paired arrangement of the pistons, such construction is nevertheless preferred as offering simplicity of construction and affording greater facility for placing and removing the wrist pins 14.

10 Claim:

An engine as characterized comprising a plurality of power units, said units each embodying a cylinder and piston reciprocatively mounted therein; a crank shaft; a connecting rod operatively uniting said

shaft and said pistons for imparting the combined thrust of said pistons on said shaft through a single rod; an explosion chamber for supplying said cylinders; and oil-injecting means for supplying said explosion chamber, said means embodying a pump operated by said connecting rod. 20

In testimony whereof I have signed my name to this specification in the presence of two subscribing witnesses.

SETH SALOMON ERICKSON.
